UNITED STATES PATENT OFFICE.

CHARLES EDWARD GALVIN, OF SPRINGFIELD, OHIO, ASSIGNOR TO THE RIDGELY TRIMMER COMPANY, OF SPRINGFIELD, OHIO, A CORPORATION OF OHIO.

PUTTY AND SCRAPER KNIFE HANDLE.

Application filed April 12, 1922. Serial No. 551,930.

To all whom it may concern:

Be it known that I, CHARLES EDWARD GALVIN, of the city of Springfield, county of Clark, State of Ohio, United States of America, have invented certain new and useful Improvements in Putty and Scraper Knife Handles, of which the following is a specification.

My invention relates to the improvement 10 in molded handles, particularly bakelite and similar compositions, for putty knives and scrapers having blades subjected to bending and torsion strains, and the objects of my invention are, first, to provide means 15 whereby the bakelite is protected against cracking when subjected to stresses induced in the tang of the handle by the blade, second, to provide means of aligning and keying ferrule in exact position.

20 I attain these objects in the accompanying drawing, in which—

Fig. 1, is a longitudinal section through my knife.

Fig. 2, is a cross section through the 25 handle.

Similar letters refer to similar parts through the several views.

My invention relates particularly to that 30 class of knives and tools with flat blade and tang, stamped from sheet steel, and which are subjected to great bending strains in use. The putty and scraper knife used by glaziers and painters belong to this class, and the usual methods of constructing the 35 handles for the same are very old, and consist of using wood as the body of the handle, either as one piece with the tang inserted, or as half pieces riveted to the tang. A ferrule is often used to bind the 40 parts as well as to give finish to the handle.

The practicability of wood for such handles can be attributed to the strength, toughness and flexibility of wood and its ability to follow without breaking the excessive bending of the steel tang of the 45 blade. Therefore, in order to use bakelite or similar compositions, which are strong and tough and will break before they will bend, for handles in such knives and tools, it becomes necessary to employ a new construction to compensate for the lack of flexibility in the bakelite. Just how I 50 accomplish this is described as follows:

By referring to Fig. 1, of the drawing, I 55 show a longitudinal section through a putty

knife having a molded bakelite handle of my invention. In this knife, the blade "A," and the tang "E" are shown as one piece and stamped from sheet steel in the usual manner, and having a shoulder "B" against 60 which the ferrule "F" is forced and held by a reinforcing insert "D" which slips over the tang "E," the insert D consisting of two members of channel form which surround the side edges of the tang and in 65 contact with the corners thereof and slightly spaced apart from each other. With this relation of the parts, the same are imbedded in molded bakelite "C" forming a finished handle. As is well known to the trade 70 when bakelite or similar substances are molded, a very high pressure and very high temperature are employed so that the two parts of the reinforcing insert D are necessarily pressed upon the tang in such a 75 way as to be in direct contact therewith but otherwise disconnected therefrom. The cross section Fig. 2, shows how the bakelite "C" incases the reinforcing insert "D," which in turn surrounds the tang "E." In 80 Fig. 1, it will be noted that the insert "D" is shorter than the tang "E," providing means for anchoring the tang in the bakelite at the butt end of the handle.

When the blade of a knife is in use, bending of the same takes place, and the point of greatest strain being at "B" in Fig. 1, where the tang joins the blade. Since the tang is a continuation of the blade, all strains in the tang concentrate at "B" and 85 decrease rapidly toward the butt end of the handle, and in order to arrest these strains before they reach the bakelite of the handle, I employ the short metal reinforcement "D" which surrounds the tang, but is not integral with it. The distinct advantage 90 thus gained is very significant, since the tang may bend or even break off at "B," which is the critical point of bending, yet the insert "D" cannot bend at the same 95 point because it ends there, and the deflection of an individual piece is zero at its end regardless of how it is strained. I also reduce the possible bending in the insert by making it short, since the bending of any individual piece is directly proportional to its length. Should my reinforcing member be made integral with the tang, these favorable conditions would 100 not exist and the bakelite, as well as the 105

insert, would be forced to follow the bending of the tang at all points, and would result in failure of the bakelite at, or near, the blade, and would not attain the objects 5 of my invention.

I find that my method of reinforcing my handle equally effective with or without the ferrule and shown as "F" in Fig. 1. However, I use the ferrule to give finish to the 10 handle and in order to make certain that it will not pull loose from the bakelite, I employ a dovetail slot, shown as "G," Fig. 1, cut in the edge of the ferrule into which the bakelite forms a key, retaining the same 15 from pulling away. The insert "D" serves to align the ferrule and hold it securely against the blade shoulder during the operation of molding the handle.

Having thus described my invention, what 20 I claim is:

1. In a tool of the character described, a blade, a flat tang integrally formed with said blade, a composition handle, and intermediate means encircling the edges of said 25 tang and overlying the sides thereof, but otherwise disconnected therefrom, whereby the tang will be stiffened independently of the material of said handle.

2. In a tool of the character described, a 30 blade, a flat tang integrally formed with said blade, with a shoulder therebetween, a pre-formed reinforcing member surrounding both the sides and edges of said tang for stiffening the same and terminating 35 at said shoulder, said member being of substantially the same width throughout its length, said reinforcing member being of a character to enable it to be slipped on said tang with a close fit but being otherwise 40 disconnected therefrom, and an outer composition handle member molded upon said tang and reinforcing member.

3. In a tool of the character described, a 45 blade, a flat tang integrally formed with said blade, with a shoulder therebetween, a pair of reinforcing members on said tang for stiffening the same and terminating at said shoulder, each member being substantially U-shaped in cross-section and of sub-

stantially the same width throughout its 50 length so as to surround one edge and portions of the sides of said tang with a close fit but otherwise disconnected therefrom, and an outer composition handle member molded upon said tang and reinforcing 55 member.

4. In a tool of the character described, a blade, a flat tang integrally formed with said blade, with a shoulder therebetween, a reinforcing member for said tang adapted 60 to be placed on said tang with a comparatively close fit in direct contact therewith, but otherwise disconnected therefrom, said reinforcing member surrounding both the sides of the tang and the edges thereof, the outer faces of those portions which surround the edges being of a rounded character, and an outer composition handle member molded upon said tang and reinforcing member.

5. In a tool of the character described, a 70 blade, a flat tang integrally formed with said blade, with a shoulder therebetween, a pair of reinforcing members on said tang and terminating at said shoulder, each reinforcing member being formed to inclose 75 one of the edges and portions of the sides of said tang with space between the edge of said reinforcing members, and an outer composition handle member molded upon said tang and reinforcing members and 80 within the space between said reinforcing members.

6. In a tool of the character described, a 85 blade, a flat tang integrally formed with said blade, with a shoulder therebetween, a stiffening member encircling the edges of said tang and overlying the sides thereof for stiffening the same, said stiffening member terminating at said shoulder and abutting against the same, a composition handle 90 molded on said tang and stiffening member, and a ferrule imbedded in the material of said handle and also abutting said shoulder.

CHARLES EDWARD GALVIN.
